OIL BURNER

Charles D. Johnson, Worcester, Mass., assignor
to Johnson Steel & Wire Company, Inc., Worcester, Mass., a corporation of Massachusetts

Application September 14, 1932, Serial No. 633,052

3 Claims. (Cl. 158—74)

This invention relates to oil burners designed for use in heating furnaces, retorts and the like.

One of the objects of the invention is to provide a burner of simple construction which can be advantageously used with heavy crude oil and which is constructed so that it is not only relatively free from carbonization but also is capable of producing perfect clean combustion of the heavy crude oil which is used as fuel.

10 Another object of the invention is to provide a novel burner which is capable of producing a long flame and which, therefore, will provide for even distribution of the heat in a relatively long retort or oven.

15 Another object of the invention is to provide an oil burner of this type in which the passage through which the heavy crude oil flows to the mixing chamber is of generous size and is free from any restricted openings that are likely to 20 become clogged by carbonization or otherwise.

In the improved burner the point at which the gasified fuel becomes ignited is spaced or separated from the jet or delivery orifice of the burner, and another feature of the invention relates 25 to novel means for regulating and controlling the spacing between the point of ignition and the jet orifice so that the point of ignition may be shifted toward or from the burner orifice as desired to produce different heating effects.

30 In order to give an understanding of the invention I have illustrated in the drawing a selected embodiment thereof which will now be described after which the novel features will be pointed out in the appended claims.

35 Fig. 1 is a sectional view through a burner embodying the invention;

Fig. 2 is a fragmentary sectional view of the mixing chamber and the means for controlling the space between the point of ignition and the 40 burner orifice;

Fig. 3 is an end view of the burner;

Fig. 4 is a section on the line 4—4, Fig. 1.

The burner herein shown is provided with a mixing chamber 1 in which the fuel oil and steam are mixed, said mixing chamber having a jet orifice 2 through which the steam and oil mixture is discharged. The fuel oil is delivered to the mixing chamber through an oil delivery pipe 3 and the passage 4 through the pipe is 45 free from restricted openings so that the oil can freely flow through the pipe 3 into the chamber 1.

Means are provided for heating the oil while flowing through the pipe 3 and before it is delivered to the mixing chamber 1. For this purpose there is provided a steam chamber 5 which

surrounds the pipe 3 and through which steam is also delivered to the mixing chamber 1. This steam chamber is formed by the space between the fuel supply pipe 3 and a steam pipe 6 which surrounds the pipe 3.

The mixing chamber 1 is formed within a mixing head 7 which is shown as a cup-shaped member that is screw threaded to the screw-threaded end 8 of the steam pipe 6, said mixing head 7 thus being supported by the pipe.

In the illustrated embodiment of the invention the jet orifice 2 is formed in a delivery nozzle 9 which is screw threaded into the end of the member 7 so as to permit its being removed, said nozzle having the wrench-receiving portion 10 for this purpose.

The steam pipe 6 is shown as connected at its rear end to a fitting 11 to which is secured a steam supply pipe 12 adapted to take steam from any suitable source of supply.

The oil delivery pipe 3 is shown as extending through the fitting 11 and as rigidly secured thereto. For this purpose the pipe 3 extends through and has screw-threaded engagement with a sleeve or bushing 13 which in turn is screw threaded into the fitting 11. The steam delivered from the pipe 12 enters the chamber 14 of the fitting 11 and then passes through the steam chamber 5 and is admitted to the mixing chamber 1 at the end of the fuel pipe 3. The presence of the steam in the steam chamber 5 serves to heat the oil flowing through the pipe 3.

The steam is preferably delivered into the mixing chamber 1 through the passage 5 under considerable pressure and as the steam and heated oil enter the mixing chamber 1 they become thoroughly mixed and the oil becomes gasified or vaporized. This mixture of steam and vaporized oil, which is under considerable pressure in the mixing chamber 1, will issue from the jet orifice 2 in the form of a jet.

This burner apparatus is intended for use in heating a retort, oven or the like and it will be understood that it will be placed so as to deliver the jet of oil, vapor and steam mixture into the combustion chamber of the furnace or oven.

One purpose of the invention is to provide a non-carbonizing burner which can be successfully used with heavy crude oil, and another purpose is to provide a burner which while using heavy crude oil as fuel yet nevertheless produces a clear flame free from smoke or soot or unburned carbon. In other words, a burner which while using crude oil will produce substantially perfect combustion.

These ends are secured by providing means for delivering a column of compressed air circum-jacent the jet opening 2. Such column of compressed air may be delivered in the form of a cylindrical column or in the form of a conical column. Where the air is delivered in the form of a cylindrical column which surrounds the jet of fuel mixture issuing from the jet orifice 2 it is found that the point of ignition of the fuel will be located at a considerable distance from the jet nozzle and the flame will be not only free from smoke or soot but will be an elongated clear flame.

15 For thus delivering this tubular column of compressed air which surrounds the jet orifice there is provided a fitting 15 which surrounds the mixing chamber 1 and which encloses an air chamber 16 into which air is delivered under pressure through a supply pipe 17. At the end 20 of the fitting adjacent the jet nozzle 9 there is an annular opening 18 through which air is delivered under pressure from the chamber 16. The air which is thus delivered under pressure through the annular opening 18 forms, as it were, a column 25 of air in the form of a tube which surrounds the jet nozzle 9. The shape of the opening 18 can be varied so as to vary the shape of this tubular column of air.

This column of air may be delivered in a direction substantially parallel to the axis of the burner or may be delivered in a sort of cone shape, depending upon the results desired. This annular air delivery opening 18 is constituted by the space between the wall of an opening 19 formed in the end 20 of the chamber 16 and the exterior of the member 7 containing the mixing chamber.

The fitting 15 within which is located the chamber 16 is formed from an interiorly screw-threaded sleeve 21 into one end of which is screw threaded 40 a plug or head 20 having the opening 19 therein. The other end of the chamber 16 is closed by means of a plug member 22 which screws into the sleeve 21 and through which the steam pipe 6 extends and with which it has screw-threaded 45 engagement.

The member 7 is formed with a cylindrical exterior surface 23 and the outer wall of the opening 19 in the plug 20 is cylindrical and presents a surface which is parallel and concentric with the cylindrical surface 23. This head 20 is also formed with the tapered or conical interior surface 24 which merges at its outer or smaller end with the surface 19.

The screw-threaded connection between the plug 20 and the sleeve 21 permits said plug to be adjusted in an axial direction with relation to the jet nozzle 9. When the parts are adjusted as shown in Fig. 1 with the cylindrical wall of the opening 19 encircling the cylindrical surface 23 of the member 7 there will be provided an annular opening 18 having concentric exterior and interior cylindrical walls. The air column or jet will issue from this opening 18 in the form of a cylindrical column which encircles the jet of fuel mixture issuing from the jet orifice 2. In Fig. 1 the jet of fuel mixture issuing from the orifice 2 is indicated at 25 and the cylindrical column of air issuing from the annular opening 18 may be indicated by the dotted lines 26.

70 With the parts thus adjusted the point at which the jet 25 of fuel mixture becomes ignited is located some distance from the jet nozzle. In the drawing, and simply for illustrative purposes, the point where ignition takes place is indicated at 75 27, and with this arrangement the flame is always

separated some distance from the nozzle member 9.

If the head 20 is adjusted forwardly into a position such as shown in Fig. 2 then the annular column of air issuing from the orifice 18 will have a somewhat conical shape and will be directed toward the jet 25 of fuel mixture. With such an adjustment the point of ignition, which is indicated at 28, will be considerably closer to the jet nozzle 9 than when the parts are adjusted as shown in Fig. 1.

A burner having this construction will produce a long flame which is highly beneficial in the heat treatment of wire, for instance where the wire is being passed through a relatively long oven or retort for treatment. With the adjustment shown in Fig. 1 the flame, and consequently the heat produced by the burner, will be distributed throughout the length of a relatively long oven or retort instead of being localized at one end thereof. This is of considerable advantage in the heat treatment of wire because it produces a better and more even heating effect.

It will be noted that the passage through which the oil flows is of generous size and is free from any restricted openings. This is of considerable advantage when heavy crude oil is used because the oil can flow freely and there are no small passages through which the oil has to flow and which might easily become clogged. Furthermore, since the point of ignition and the flame is kept spaced a considerable distance from the jet nozzle the carbonizing of the burner is reduced to a minimum and a burner is provided which can be operated for long periods of time without any appreciable carbonizing effect.

A further advantage of this construction is that owing to the manner in which the compressed air is used the flame which is produced will be a clear flame free from smoke or carbon. 115 In other words, it produces a flame resulting from perfect combustion of the heavy crude oil which is fed to the burner.

I claim:

1. An oil burner comprising an oil feed pipe, a steam pipe surrounding the oil feed pipe, a mixing head carried by the steam pipe and provided with a mixing chamber with which both the steam pipe and the oil feed pipe communicate, said mixing head also having a delivery jet orifice leading from the mixing chamber and through which a jet of steam and oil mixture is delivered, a fitting surrounding the mixing head and providing an air chamber exterior to said head, means for delivering air under pressure to said air chamber, said fitting and mixing head providing an annular air delivery opening adjacent to and surrounding the delivery jet orifice and through which a tubular column of air is delivered which encircles the jet of oil and steam mixture. 130 135

2. An oil burner comprising an oil feed pipe, a steam pipe surrounding the oil feed pipe, a mixing head carried by the steam pipe and provided with a mixing chamber with which both the steam pipe and the oil feed pipe communicate, said mixing head having a delivery nozzle provided with a delivery jet orifice through which a jet of steam and oil mixture is delivered, a fitting surrounding the mixing head and providing an air chamber exterior to said head, said fitting having an end member provided with an opening larger than and surrounding the delivery nozzle thereby providing an annular air delivery opening, and means to deliver air under pressure to said air chamber, said air issuing from the chamber through said 150

annular air delivery opening and forming a tubular column of air which surrounds the jet of oil and air mixture issuing from the delivery jet orifice.

5 3. An oil burner comprising an oil feed pipe, a steam pipe surrounding the oil feed pipe, a mixing head carried by the steam pipe and provided with a mixing chamber with which both the steam pipe and the oil feed pipe communicate, said mixing head having a delivery nozzle provided with a delivery jet orifice through which a jet of steam and oil mixture is delivered, a fitting surrounding the mixing head and providing an air chamber exterior to said head, said fitting having an end

15

member provided with an opening larger than and surrounding the delivery nozzle thereby providing an annular air delivery opening, and means to deliver air under pressure to said air chamber, said air issuing from the chamber through said annular air delivery opening and forming a tubular column of air which surrounds the jet of oil and air mixture issuing from the delivery jet orifice, said end member being adjustably carried by the fitting, whereby the position of the annular air delivery opening may be adjusted relative to the delivery end of the delivery nozzle.
